ATTORNEY

UNITED STATES PATENT OFFICE.

THOMAS HILL, OF JERSEY CITY, NEW JERSEY.

CART.

SPECIFICATION forming part of Letters Patent No. 663,227, dated December 4, 1900.

Application filed June 13, 1900. Serial No. 20,142. (No model.)

To all whom it may concern:

Be it known that I, THOMAS HILL, a citizen of the United States, and a resident of Jersey City, in the county of Hudson and State of New Jersey, have invented certain new and useful Improvements in Carts and other Vehicles, of which the following is a specification.

The invention relates to improvements in carts and other vehicles, and pertains more particularly to the means hereinafter described for mounting the cart-body upon the shafts or booms.

The invention consists of the novel constructions, arrangements, and combinations of parts hereinafter described, and particularly pointed out in the claims.

The invention will be fully understood from the detailed description hereinafter presented, reference being had to the accompanying drawings, in which—

Figure 1 is a side elevation, partly in section and partly broken away, of a cart constructed in accordance with and embodying the invention. Fig. 2 is an enlarged side elevation, partly in section, of a portion of same. Fig. 3 is a vertical transverse section of same on the dotted line 3 3 of Fig. 2. Fig. 4 is a detached bottom view of the cap which fits upon the upper central portion of the spring, and Fig. 5 is a detached top view of the lower plate which co-operates with the cap shown in Fig. 4 in inclosing the central portion of the spring.

In the drawings, 10 designates the usual cart-wheels, 11 the body of the cart or vehicle, and 12 one of the shafts or booms of the cart.

Upon opposite sides of the cart-body 11 are rigidly secured the brackets 13, formed with the trunnions 14, upon which the cart-body is mounted. The trunnions 14 and brackets 13 are of known construction, having been illustrated in Letters Patent No. 420,941 granted to me on February 11, 1890.

Upon each side of the cart-body 11 is provided a bracket 13, having the trunnion 14, and upon each shaft or boom 12 is provided a spring 15 and cap 16 thereon, said cap having above said spring the circular opening or bearing 17 to receive the trunnion 14, connected with the cart-body, whereby said

trunnion and the cart-body become supported upon the said springs 15. The springs 15 are leaf-springs of elliptic order and are held upon and secured to the plates 18, which are fastened upon the shafts or booms 12 and have at their opposite ends the upturned ears 19, between which, upon bolts 20, the ends of the springs 15 are retained. The springs 15 will comprise a suitable number of leaves, as shown, and at one end the lower leaves of said spring will be shaped to form the eye 21, through which the bolt 20 at the said end of the spring will pass, and at the other end of the spring 15 the lower leaves thereof will be bent to form the hook 22 to pass upon the bolt 20 at that end of the spring, as shown at the right-hand side of Fig. 2. The eye 21 at one end of the spring 15 serves to hold that end of the spring in rigid position, while the hook 22 at the other end of the spring permits of the spring having at its hook end a longitudinal sliding motion under the variations of the load which may come upon it. The hook formation 22 at one end of the spring 15 co-operates with the bolt 20 in serving as a stop limiting the inward motion of the spring, but permits said spring to have an endwise-sliding motion between the ears 19 at the right-hand end of the plate 18. The plate 18, in addition to being provided with the ears 19 and bolts 20, possesses along its longitudinal edges the ribs 23, which strengthen the plate 18. The plate 18 carries the spring 15, and said spring 15 when in use exerts all of its wear or frictional action against said plate 18 and has no prejudicial effect upon the shafts or booms 12. It does not make any difference at which end of the spring 15 the hook formation 22 is located, but in the present instance the hook formation 22 is at that end of the spring 15 adjacent to the rear end of the shafts or booms 12. The middle portions of the leaves of the springs 15 are connected together by means of the bolts 24, and said portions of the leaves of the spring 15 are also bound together by the cap 16, lower plate 25, and U-shaped bolts 26. The plate 25 is a simple strip of metal having its ends turned slightly downward, as shown in Fig. 2, and having at its central portion the recess 27 to accommodate the head of the bolt 24, and said plate

25 is of substantially the same width as the spring 15 and practically coextensive in length with the cap 16. The cap 16 is of cast metal and fits snugly down upon the spring 15, and said cap 16 at its apex is furnished with the aperture 17 for the trunnion 14, while the sides of said cap 16 extend downward upon and inclose the side edges of the said spring 15, as more clearly illustrated in 10 Figs. 1 and 3. At its four corners the cap 16 is formed with the tubular ears 28, (clearly shown in Fig. 4,) which extend laterally outward from the depending sides of the cap 16 and receive the vertical members of the 15 U-shaped bolts 26, as shown in Fig. 1. The bolts 26 have nuts applied upon their upper ends, extending upward through the tubular sleeves 28, and the bend or loop portions of said bolts 26 extend transversely below the 20 plate 25 and spring 15 and bind said plate 25 against the lower surfaces of the said spring. In order to as far as possible avoid all noise from the cart, I provide intermediate the lower surfaces of the cap 16 and the 25 adjacent upper surface of the spring 15 a strip of rubber or other suitable material 29, which extends the full length of the cap 16 and passes over the nut on the bolt 24, as shown in Fig. 2. The lower surface of the 30 cap 16, directly below the bearing-aperture 17, is recessed, as illustrated in Figs. 2, 3, and 4, to accommodate the nut on the upper end of the bolt 24. It will appear obvious that when the cap 16, plate 25, and bolts 35 26 are applied upon the spring 15 they very materially increase the strength of said spring and afford a rigid support for the trunnions 14 on the cart-body. By tightening the nuts on the upper ends of the bolts 26 the plate 40 25 and cap 16 may be drawn toward one another and against the upper and lower surfaces of the springs with all of the firmness and rigidity that could be desired. The recess 30 in the cap 16 and the recess 27 in the 45 plate 25, respectively receiving the nut and the head of the bolt 24, aid in preventing said cap and plate from having any sliding motion upon the spring 15, and said recesses also facilitate the proper initial placing of 50 said cap and plate upon said spring. The bolts 26 firmly clamp the cap 16 and plate 25 upon the spring and the downwardly-turned ends of the plate 25 aid in preventing any sliding of said plate from position during the 55 use of the cart. The tubular ears 28 on the cap 16 maintain the proper position of the bolts 26, since said ears retain the vertical members of said bolts in proper vertical position.

60 The plate 18 is secured upon the shafts or booms 12 by means of the bolts 31, 32, and 33, the said bolts also passing through the plate 34, applied to the lower side of the shafts or booms 12, as indicated in Fig. 2. The 65 bolts 31 at their lower portions are connected by the plate 35, and said plate, with the lower portion of the bolts 31, together with

the recess 36, formed in said plate 34, constitute a frame for the end of the axle 37, upon which the cart-wheels 10 are mounted. The 70 bolts 32 pass through the plate 34, shaft or boom 12, and plate 18 and aid in binding the plates 18 and 34 upon the upper and lower surfaces of the shaft 12, greatly strengthening the structure and preventing the bolts 32 75 from having any special wear or influence upon said shafts. The bolt 33 in the present instance passes through the shaft 12 and plate 18. The plate 34 at each side of the cart is formed with a recess 38 to receive the 80 end of a transverse bar 39, said bar 39 extending transversely across and connecting the shafts 12 and having its ends secured within the recess 38 of the plates 34 by means of bolts 40, which extend upward through the 85 plates 34, shafts 12, and plates 18. The bolts 40, while securing the transverse bar 39 in position, also aid in binding the plates 34 and plates 18 upon the shaft 12.

By means of the construction hereinbefore 90 described I produce a very efficient, simple, and durable cart or vehicle and one which can withstand substantially any reasonable amount of abuse without injury to the springs 15. The construction is also one which in 95 itself preserves the springs 15 from breakage and avoids the result of any accident which might occur by the breakage of the springs at the bolt 24, which is the only point at which the springs are in any way cut or weakened. Should the springs break at the bolt 24, the cap 16, plate 25, and bolts 26 would have the effect of keeping the springs together at their middle portions until the cart could 100 reach a proper destination for its repair. My 105 experience is, however, that the springs 15, mounted in the manner and provided with the device hereinbefore described, are not at all liable to breakage, but are of great durability and add very much to the utility and 110 longevity of the cart.

When the invention is applied to a dumping-cart, the booms 12 will extend forward to a sufficient extent to constitute the shafts for the horse; but in other classes of vehicles the 115 booms 12 will constitute a part of the bed or frame forming, with the wheels and axles, the running-gear.

What I claim as my invention, and desire to secure by Letters Patent, is—

1. The running-gear, combined with the vehicle-body provided on its opposite sides above its bottom with the side trunnions or pivots, the semi-elliptic springs 15 mounted on the shafts 12 and extending upward at 125 their middle portions on opposite sides of said body, the caps 16, each in one integral piece, on the center of said springs and extending downward on opposite sides thereof and having the transverse bearing-apertures 130 17 for said trunnions and also having the vertical outwardly-extending tubular ears 28, the bolts 26 of U shape encompassing the sides and lower surfaces of said springs and

having their side members within said ears 28, and the securing-nuts on the upper ends of said bolts above said caps; substantially as set forth.

5 2. The running-gear, combined with the vehicle-body provided on its opposite sides above its bottom with the side trunnions or pivots, the semi-elliptic springs 15 mounted on the shafts 12 and extending upward at 10 their middle portions on opposite sides of said body, the caps 16, each in one integral piece, on the center of said springs and extending downward on opposite sides thereof and having the transverse bearing-apertures 15 for said trunnions and also having the vertical outwardly-extending tubular ears 28, the plates 25 below said springs and substantially coextensive with said caps and having the downwardly-extending end portions, the 20 bolts 26 of **U** shape engaging at their lower transverse portion the ends of said plates 25 and having their side members within said ears 28, and the nuts on the upper ends of said bolts above said caps; substantially as 25 set forth.

3. The running-gear, combined with the vehicle-body provided on its opposite sides above its bottom with the side trunnions or pivots, the semi-elliptic springs 15 mounted 30 on the shafts 12 and extending upward at their middle portions on opposite sides of said body, the caps 16, each in one integral piece, on the center of said springs and extending downward on opposite sides thereof and having the transverse bearing-apertures 17 for said trunnions and also having the vertical outwardly-extending tubular ears 28, the plates 25 below said springs and substantially coextensive with said caps, the strip of 35 soft material 29 extending continuously over the entire lower surface of the top of said caps, the bolts 26 of **U** shape engaging at their lower transverse portion the ends of said plates 25 and having their side members 40 within said ears 28, the nuts on the upper ends of said bolts above said caps, and the bolts 24 connecting the leaves of said springs at their center; said caps 16 and said plates 25 being respectively provided with the recesses 30 and 27 to receive the head and nut of 45 said bolts 24; substantially as set forth.

4. The running-gear, the vehicle-body provided on its opposite sides above its bottom with the side trunnions or pivots, the semi-55 elliptic springs 15 mounted on the shafts 12 and extending upward at their middle portions on opposite sides of said body, and the caps 16 on the center of said springs to aid in securing the leaves of the latter and having 60 the transverse bearing-apertures for said trunnions, said springs having at one end the

eye 21 and at the other end the hook 22, combined with the elongated plates 18 secured upon the upper surface of said shafts 12 and having at their opposite ends the upturned 65 ears 19 and the bolts 20, one of said bolts passing through the said eye and the other of said bolts passing within the said hook 22; substantially as set forth.

5. The running-gear, the vehicle-body provided on its opposite sides above its bottom with the side trunnions or pivots, the semi-elliptic springs 15 mounted on the shafts 12 and extending upward at their middle portions on opposite sides of said body, and the 70 caps 16 on the center of said springs to aid in securing the leaves of the latter and having the transverse bearing-apertures for said trunnions, combined with the elongated plates 18 secured upon the upper surface of said 75 shafts 12 and having at their ends the upturned ears receiving between them the ends of said springs, the elongated plates 34 applied upon the lower surface of said shafts 12 below said plates 18, and the bolts 31 and 32 80 passing through said plates 34, shafts 12 and plates 18, said bolts 31 being extended below said plates 34 and connected by the plate 35 to form the frame for the axles; substantially 85 as set forth.

6. The running-gear, combined with the vehicle-body provided on its opposite sides above its bottom with the side trunnions or pivots, the semi-elliptic springs 15 mounted on the shafts 12 and extending upward at 90 their middle portions on opposite sides of said body, the caps 16, each in one integral piece, on the center of said springs and extending downward on opposite sides thereof and having the transverse bearing-apertures 17 for 95 said trunnions and also having the vertical tubular ears 28, the plates 25 below said springs and substantially coextensive with said caps, the strip of soft material 29 extending over the lower surface of the top of said caps, the 100 bolts 26 of **U** shape engaging at their lower transverse portion the ends of said plates 25 and having their side members within said ears 28, the nuts on the upper ends of said 105 bolts and said caps, and the bolts 24 connecting the leaves of said springs at their center, said caps 16 and said plates 25 being respectively provided with the recesses 30 and 27 to receive the head and nut of said bolts 24; 110 substantially as set forth.

Signed at New York, in the county of New York and State of New York, this 11th day of June, A. D. 1900.

THOMAS HILL.
